UNITED STATES PATENT OFFICE.

PHILIP STEINBOCK, OF NEW YORK, N. Y.

SELF-LUBRICATING DUSTPROOF SEWING-MACHINE.

1,380,120.

Specification of Letters Patent. Patented May 31, 1921.

Application filed May 25, 1920. Serial No. 384,027.

To all whom it may concern:

Be it known that I, PHILIP STEINBOCK, a citizen of the United States, residing at New York, county of New York, and State of New York, have invented certain new and useful Improvements in Self-Lubricating Dustproof Sewing-Machines, of which the following is a specification.

This invention relates to improvements in self-lubricating, dust-proof sewing machines, particularly machines for sewing straw plait for straw hats, and for similar purposes.

It is the principal object of the invention to provide means whereby the bearings of such machines, which are usually high-speed power driven machines, are automatical or self-lubricating for a long period, for instance for several days or weeks depending upon the amount of lubricant stored in the machine.

Another object of the machine is the provision of means for automatically oiling especially quick moving parts, which could not be oiled by direct application of the lubricant without the danger of splashing the oil, by means of oil-soaked cotton or waste-tape so called fuses saturated with the lubricant.

A further object of the invention consists in providing a machine of the character specified which can be oiled by anyone or rather which is self-oiling and needs only the attendance of unskilled labor to effect its lubrication, thus saving expenses for skilled labor.

Other features of my improved machine will become apparent as the description thereof proceeds and will be more fully set forth hereinafter.

With these and other objects in view my invention consists in the combination and arrangement of parts shown in the accompanying drawings, and particularly pointed out in the appended claims, it being understood that changes in the form, proportion, and minor details may be made within the scope of the claims without departing from the spirit or scope of my invention or sacrificing any of the advantages of the invention.

In the accompanying drawings—

Figure 1 is a front elevation of my self lubricating sewing machine constructed according to the present invention.

Fig. 2 is a top plan view thereof, taken along line 2—2 of Fig. 1.

Fig. 3 is an end view of the machine the view being taken along line 3—3 of Fig. 1.

Fig. 4 is another end view of the machine seen from the left Fig. 1.

Fig. 5 is a top plan view partly in section 60 along line 5—5 of Fig. 1.

Fig. 6 is a sectional view, the section being taken along line 6—6 of Fig. 5.

Fig. 7 is a sectional view, the section being taken along line 7—7 of Fig. 5. 65

Fig. 8 is a detail view of a feed bar.

Fig. 9 is a detail view of the parts used for assembling the feed bar, Fig. 8.

Fig. 10 is a top plan view of the frame after removal of the cover and machine 70 parts.

Fig. 11 shows in detail views the housings for the eccentrics and shaft.

Fig. 12 is a sectional view, the section being taken on line 12—12 of Fig. 10. 75

Fig. 13 is a detail view of one of the wick holders.

Fig. 14 is a front sectional view of the machine the section being taken on line 14—14 of Fig. 2. 80

Corresponding parts in the several figures of the drawings are designated by like characters of reference.

The machine frame 10 is provided at one of its sides with the customary operating 85 wheel 11 secured to operating shaft 12 and integrally made with a belt pulley 13 on its inner face. A cup 14 is provided on the side of the frame adapted to be filled with oil or a lubricant in which the customary eccentric 15 and the lower end of excenter bar 16 are moving with the rotating shaft, and the cup is entirely closed against the intrusion of dust and the splashing of oil, a washer 17 being provided on the shaft in 90 order to prevent any leaking of the lubricant toward the outside at the place where the shaft 12 enters the cup or chamber 14. 95

The bar 16 and its connections are incased in a dust proof casing 18 which is removably 100 secured to the chamber 14. The casing 18 is closed at the top by a plate 19 carrying the tensioning device 20 and thread guide 21.

Within the casing 18 the upper end of the bar 16 is secured by the customary well 105 known split bearing 22 to the inner end of the rocker arm 23.

This split bearing 22 has in its upper edge an opening for the reception of one end of a wick 24, the other end of which is un- 110

twisted as at 25 and depends into an oil chamber 26, an eye 27 being provided on the side of the arm 23 to hold and guide the wick. The rocker arm 23 is rocking on a shaft 28 transversely passed through the chamber 26 and having its ends extended therethrough on both sides. The extensions on front and rear of the casing 10 are each provided with a tensioning annulus or sleeve 29 secured on the shaft 28 and bearing with their inner faces against a socket 30, shaped on one side into an oil gage 31. From the shaft 28 an oil supplying wick 32 engaging with one end said shaft, is guided with its other untwisted and branched end 33 into the oil reservoir 26 and is held intermediate its ends to the arm 23 by means of a screw 34.

The arm 23 is provided at its upper edge, intermediate its ends with a thread guiding eye 35 and the front end of the arm 23 is secured in the ordinary well known manner as at 36, to an operating block 37 secured at 38 to the movable needle bar 39 intermediate the ends thereof. The needle bar 25 is provided at its upper end with an eye 40 for the passage of the thread which is guided from the eye 35 to a guide 35' and is then guided through a slot 41 of a bracket 42 secured to the side of an oil cup or reservoir 43. The thread finally passes through a guide 44 on the end of frame 10 to the needle 45 secured in the lower end of the needle bar in the customary well known manner.

35 A thread tensioning device 46 has an inner projection 47 pressing the free end of a spring 48 against the thread guided through the slot 41 of the bracket 42, while the other end of said spring is secured in 40 the device 46.

45 A thread tension release arm 49 is secured to the rear of the arm 23 and is made in two pieces which are adjustably connected at their meeting ends by means of a sleeve 50 integrally made with one of the pieces of arm 49 and provided with a central hole through which the other piece of the arm is passed as at 51, while a fastening screw 52 is passed through the end of the sleeve 50 into engagement with arm 49 as best seen in Fig. 2.

The free outer end of arm 49 is passed through the oil reservoir 43 in engagement with spring 48.

55 As shown in Fig. 10 the oil cup 43 has an inner oil receptacle 53 and a block 54 provided with passages for the needle bar and the presser bar, and provided with chambers 55 communicating with the passages for the needle and presser bars for the reception of wicks 56, 57 supplying said needle and presser bars with oil.

The presser bar is designated at 58 and stands as customary under the tension of a 65 spring not shown, within the frame 10, the

tension of which can be regulated by means of a screw 59 (Fig. 4), while the lifter 60 engages with its upper shoulder a pin 61 on the presser bar.

The presser bar carries at its lower end 70 a foot 62 engaging with its curved and forked rear end a groove of the presser bar, the lower end of which carries a nut 63, holding the foot with its curved part to the presser bar. 75

The front part of the foot 62 is cut-away to provide a passage for the needle 45, while a regulating screw 64 adapted to regulate the plait guard can be locked in its adjusted position by means of a lever 65. 80

The throat plate 66 is provided with an opening for the passage of the needle and underneath of this opening a lower stitch forming device 67 (Fig. 5) having an opening 68 is provided which also forms a bearing 69 for the free end of the shaft 12. 85

In an opening in the throat plate 66 underneath and below the presser foot 62 a feeding device 70 is arranged which can be raised and lowered against the throat plate 90 by means of an adjusting screw 71 (Figs. 8 and 9) adapted to raise and lower a carrier plate 72 to which the feeding device 70 is secured by a screw 73. A screw 74 and plate 75 secure the entire device described 95 before when the parts are assembled to the outer end of an arm 76, having a U-shaped member 77 adapted to straddle the side wall 78 of a casing or box 79 adapted to be filled with oil and closed on top by a cover 80 secured upon the side and end walls by means of screws 81. Within this casing the arm 77 is made integral with a crank body 82 on shaft 12 and its free arm forms part of a rocking frame 83 within the casing 79. 100 105

A stitch regulator of well known construction generally indicated at 84 is provided at the front part of the machine and comprises a sliding index plate 85 provided with a longitudinal slot 86 through which 110 the stem of an index finger 87 is extending and secured to the casing or front wall 88 of the oil box 79 is a screw, holding the index plate in frictional engagement with the wall 88 and having a guide arm 89 for 115 a material guiding plate 90, while the lower part of the plate 85 is provided with teeth 91 adapted to be engaged by the teeth of a gear 93 on the shaft of an operating knob 92 adapted to displace the plate in order 120 to regulate the distance of the rows of stitches on each plait.

The front plate 88 of the oil reservoir 79 is provided with an oil gage 94 to indicate the level of the oil within box 79. As 125 shown in Figs. 12, 13 and 14 wick holders 95 are provided at the bottom of the box 79 in which wicks 96 are held by springs 97 with their upper ends in engagement with the shaft 12 in order to permanently supply 130

oil to the same if the level of the oil contained within the box 79 has sunk below the level of said shaft.

Intermediate their ends the presser bar 58 and the needle bar 39 are guided through an oil receptacle 98 (Fig. 4) provided with front and rear cups 99.

As shown in Figs. 5 and 6 the oil receptacle 79 contains the rocker frame 83, the lower part of which is rocking on shaft 100. The frame 83 forms a bearing for a shaft 101 to which is secured a sleeve 102 at the end of an arm 103, the front part of which is secured to a sleeve 104 on shaft 12. The arm 103 is provided with upper openings to receive oil.

Having thus described my invention what I claim and desire to secure by Letters Patent of the United States is—

- 20 1. In a sewing machine of the character described, having a dust proof, chambered casing including an excenter bar, an oil receptacle or chamber, a split-bearing for the excenter bar of the machine having an opening, and a wick adapted to enter the opening in said bar and to extend with its free untwisted or branched ends into said oil chamber, and means for guiding said wick intermediate its ends.
- 30 2. In a sewing machine of the character described having a dust proof, chambered casing, in combination with an oil containing casing, a rocker arm, a shaft passed transversely through the casing on which said arm is pivoted, said shaft having its arms extended through the casing on both sides thereof, and a sleeve, or annulus on each end of said shaft engaging said arm for regulating its frictional motion, and a socket for one of said sleeves constituting an oil gage for indicating the level of the oil within said casing.
- 40 3. In a sewing machine of the character described having a dust proof, chambered casing in combination with an oil containing casing, a rocker arm, a shaft passed transversely through the casing on which said arm is pivoted, a wick entering with its lower branched end the oil within said casing and

with its upper end engaging said transverse shaft, and means for guiding said wick intermediate the ends thereof.

4. In a sewing machine of the character described having a dust proof, chambered casing in combination with the needle- and presser bars thereof, an oil cup, a chambered block on said cup for the passage of the needle- and presser bars, and providing channels connecting said cup with the passages of the needle- and presser bars, wicks in said cup entering said channels for engaging said presser- and needle bars, and a screw passed through said cup for regulating the presser bar tension.

5. In a sewing machine of the character described having a dust proof, chambered casing, the combination of an oil reservoir forming part of the machine casing, an operating shaft of the machine passed through said oil reservoir, rocker elements connected with said shaft and located within said reservoir, a fabric feeding device, means connecting said rocker element with said feeding device, and an oil gage at the front wall of said reservoir for indicating the level of the oil contained therein.

6. In a sewing machine of the character described having a dust proof, chambered casing, the combination of an oil reservoir and an operating shaft passed through said reservoir with a plurality of wick holders at the bottom of said reservoir, springs in said holders, and wicks held in said springs adapted to engage with their upper free ends said shaft for lubricating the same even if the oil level within said reservoir has fallen below said shaft.

7. In a sewing machine of the character described having a dust proof, chambered casing, the combination with the frame of the machine with a needle and presser bar of an oil receptacle intermediate the ends of said needle and presser bar, and cups at the front and rear ends of said receptacle.

In testimony whereof I have affixed my signature.

PHILIP STEINBOCK.
